UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A CARD-MOUNT.

SPECIFICATION forming part of Design No. 33,059, dated August 14, 1900.

Application filed June 4, 1900. Serial No. 19,077. Term of patent 7 years.

To all whom it may concern:

Be it known that I, JOHN P. ODGERS, a citizen of the United States, and a resident of Philadelphia, Pennsylvania, have invented or produced a new and original Design for a Card-Mount, of which the following is a specification.

My design is fully illustrated in the accompanying drawings, in which—

10 Figure 1 is a face view of the card-mount; and Fig. 2 is a sectional view of the same on the line 2 2, Fig. 1.

15 The essential feature of the design is the raised border surrounding the space for the picture and having at top and bottom scrolls consisting of connected convolutions of varying size.

In the drawings the raised border is shown

as composed of an inner and larger rib *a* and an outer and smaller rib *b*, and extending outwardly beyond this rib *b*, at top and bottom of the mount, are the scrolls *c*, which consist of connected convolutions largest at the center of the scroll and gradually diminishing in size toward each edge of the scroll. 20 25

I claim—

10 The design for a card-mount substantially as described and as shown in the accompanying drawings.

15 In testimony whereof I have signed my name to this specification in the presence of two subscribing witnesses. 30

JOHN P. ODGERS.

Witnesses:

WILL. A. BARR,
JOS. H. KLEIN.
